UNITED STATES PATENT OFFICE.

GEORGE R. SHANKLIN, OF PORTLAND, OREGON.

BURNER.

No. 884,869.

Specification of Letters Patent.

Patented April 14, 1908.

Application filed May 9, 1907. Serial No. 372,757.

To all whom it may concern:

Be it known that I, GEORGE R. SHANKLIN, a citizen of the United States, residing at Portland, in the county of Multnomah and State of Oregon, have invented new and useful Improvements in Burners, of which the following is a specification.

This invention relates to a burner for furnaces, stoves or other heating apparatus of 10 that type designed for use with liquid hydrocarbons, and relates more particularly to a burner of that type in which steam is instrumental in gasifying the fuel and producing therewith a highly combustible mixture 15 whereby the burner can operate with an intense blue flame and without smoke or soot.

The invention has for one of its objects to improve and simplify the construction and operation of devices of this character so as to 20 be comparatively easy and inexpensive to construct, thoroughly efficient in practice, and readily started and controlled.

A further object is the provision of a mixing chamber or cylinder that is heated by the 25 flame and serves as a deflector for the latter whereby the chamber is sufficiently heated to maintain the steam an an effective temperature for vaporizing the liquid hydro-carbon discharged into the steam, thus producing 30 a highly combustible mixture and enabling the gas to absorb a large quantity of steam and without causing carbonization and clogging of the burner.

Another object of the invention is the provision of a retort or cylinder having a steam 35 generator therein and connected with separate sources of water and fuel supply for delivering water to the generator and oil to the retort to be vaporized and mixed with the 40 steam therein, and also provided with a mixture tube having a jet discharging opening for directing the flame against the retort or cylinder and maintaining it in heated condition, the water and fuel supply pipe being 45 provided with plugs of asbestos or the like through which the liquids pass.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a central horizontal section

of the burner. Fig. 2 is a vertical central section. Fig. 3 is a transverse section on line 3—3.

Similar reference characters are employed 60 to designate corresponding parts throughout the several views.

Referring to the drawing, 1 designates a hollow body or retort in the form of a cylinder having closed ends and preferably constructed of comparatively thin walls and flattened at its bottom. The head 2 of the cylinder or retort is provided with apertures 3 and 4 into which extend respectively, oil and water supply pipes 5 and 6 that are provided with controlling valves 7 and 8. The openings 3 and 4, which are of the same size, are provided with bushings 9 which receive coupling members 10 screwed on the pipes 5 and 6. The discharge end of the pipe 6 is contracted to form a nozzle. Extending longitudinally within the retort or cylinder 1 and at one side of the center thereof is a generator 11 in the form of a tube closed at its inner ends and threaded into the bushing 9 at 70 the opening 4, whereby the generator is removably supported in position. The generator tube is disposed over the inner end of the water pipe and at a point intermediate its ends, has a single upwardly discharging 75 opening 12 by which steam is conveyed to the retort 1. In the pipes 5 and 6 are plugs of asbestos and gauze which readily permit the hydro-carbon oil and water to freely pass into the retort and generator respectively. 80 The tube 11, which is removable through the opening 4 with the bushing 9, extends somewhat short of the head 13 of the retort, and disposed under the latter is an L-shaped mixture tube 14 having its inner end threaded in 85 an opening 15 arranged in the bottom of the retort and between the head 13 and inner end of the generator 11. The front end of the mixture tube 14 is closed by a cap 16 and the top side of the tube has a jet discharging 90 opening 17 for directing a jet of vapor upwardly toward the retort.

In practice, the burner is located in the firebox of a furnace or boiler in any suitable position, and to start the burner, a fire or 105 flame is kindled under the retort 1 so as to heat the walls thereof to a high temperature. The water valve 8 is slightly opened to permit a small quantity of water to enter the generator 11, whereupon it immediately vaporizes and escapes through the opening 12 to the retort where it is further expanded and 110

superheated. At about this time, the oil valve 7 is opened to admit a small quantity of liquid hydro-carbon to the retort, which, upon coming in contact with the hot metal 5 of the retort and superheated steam, is immediately gasified and mixed with the steam so that a rich combustible mixture is produced, and this superheated mixture passes out through the tube 14 and discharges from 10 the burner. The mixture is ignited automatically by the kindling flame, whereupon the latter can be extinguished and removed and the burner will continue in regular operation. The flame forcibly impinges on the 15 exterior of the retort and is baffled by the latter and spread outwardly so as to take up a large percentage of air and produce a flame of great volume for effectively heating the water-back, coils or other heating elements 20 of the boiler or furnace. By introducing the liquid hydro-carbon directly into steam, several beneficial results are obtained, namely, total freedom from carbonization and clogging of the burner, the production of a better 25 mixture than is possible where the water and fuel are vaporized separately and then mixed, since the oil can be vaporized by the steam immediately and take up a larger volume of steam and hence of oxygen.

30 From the foregoing description, taken in connection with the accompanying drawing, the advantages of the construction and of the method of operation will be readily apparent to those skilled in the art to which the invention appertains, and while I have described the principle of operation of the invention, together with the apparatus which

I now consider to be the best embodiment thereof, I desire to have it understood that the apparatus shown is merely illustrative 40 and that such changes may be made when desired, as are within the scope of the claims.

Having thus described the invention, what I claim is:—

1. A burner comprising a retort having 45 openings, liquid and oil supply pipes extending into the openings, bushings around the pipes at the openings, a straight generator tube closed at one end and provided with a jet opening at an intermediate portion and 50 having threaded engagement with the bushing for the liquid supply pipe, a tube disposed under the retort and having threaded engagement therewith at one end and arranged to cause the flame of the burner to 55 heat the retort, and porous plugs in the supply pipes adjacent the discharge ends thereof, and controlling valves in the pipes.

2. A burner comprising a closed retort having openings of the same size, bushings 60 in the openings, a generator supported solely on one of the bushings, a water supply pipe extending into the outer end of the generator, a coupling member connecting the said supply pipe with the bushing, a fuel supply pipe extending into the second bushing, and a coupling member secured in the fuel supply pipe to the bushing.

In testimony whereof, I affix my signature in presence of two witnesses.

GEORGE R. SHANKLIN.
